UNITED STATES PATENT OFFICE.

GEORGE W. SHAMP, OF BUFFALO, NEW YORK, ASSIGNOR TO THE ACME
MANUFACTURING COMPANY, OF SAME PLACE.

PAPER-FOLDING MACHINE.

SPECIFICATION forming part of Letters Patent No. 349,322, dated September 21, 1886.

Application filed October 9, 1885. Serial No. 179,376. (No model.)

To all whom it may concern:

Be it known that I, GEORGE W. SHAMP, a citizen of the United States, residing at Buffalo, in the county of Erie and State of New York, have invented certain new and useful Improvements in Paper-Folding Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates particularly to certain improvements in a paper-folding machine for which Letters Patent No. 303,255 were granted, August 12, 1884, to Frederick G. Beach. The construction covered by such patent involved the combination, with a series of folding-flies, of a knife and cylinders, and also oscillating blades, combined with folding-flies for creasing the sheets preparatory to folding same. My improvements upon these constructions, together with other improved details, will be more fully hereinafter described and claimed.

In the drawings, Figure 1 is a top plan view of my improved folding-machine. Fig. 2 is a right-hand side elevation, and Fig. 3 is a left-hand side elevation, of Fig. 1. Figs. 4, 5, and 6 are different views of my improved manner of pivoting the intermediate flies. Figs. 7 and 8 are respectively end and side views of the creasing-knife which operates between the cylinders. Fig. 9 is a view of the creaser on the intermediate fly. Figs. 10, 11, 12, and 13 are other detail views.

In the drawings, *a* is the frame-work upon which the folding apparatus is mounted. The unfolded sheet is laid on the folder, covering the large and intermediate flies, cylinder, and raised portions *a'* and *a''* of frame. The large fly consists of the inner bar, *b*, pivoted to the frame-work *a*, the outer bar, *b'*, and the cross bars or slats *b''*.

c is the intermediate fly, occupying one-half of the remainder of the frame *a*, and *d* is the smaller fly adjacent to the fly *c*. In the remaining space, about centrally located between the raised portions *a'* and *a''*, are the revolving cylinders *e e*.

The manner of reciprocating the large fly *b* is as follows: *f* is the main shaft secured longitudinally in the frame-work *a*. Upon this shaft is the bevel gear-wheel *f'*, which intermeshes with the bevel gear-wheels *f'' f'''*, secured, respectively, to the transverse shafts *f'' f'''*. *f''* is the sprocket-wheel by means of which the main shaft *f* is revolved. At the outer end of the shaft *f''* is keyed a pulley, *f'''*, having a segmental gear, *f''''*, projecting outwardly from its periphery. Upon the corresponding outer end of the pivoted bar *b* of the large fly is the segmental gear *f''''*. Upon the outer end of the shaft *f'''* is a segmental gear, *f''''''*, and upon the corresponding end of the pivoted bar *b* is the segmental gear *f'''''''*. In reciprocating the large fly the motion of the shaft *f* is communicated to cross-shafts *f'' f'''*, and the segmental gear *f''''* upon shaft *f''* first engages with the gear *f'''''''* upon the bar *b*, which has the effect of turning the fly *b* over upon the intermediate flies and cylinders. It is instantly turned back to its normal position by the succeeding engagement of the gear *f''''''* upon shaft *f'''* with the gear *f'''''''* upon the bar *b*.

The intermediate and small flies, *c* and *d*, are reciprocated as follows: The inner bar, *c'*, of the fly *c* is pivoted in the frame-work *a*, and has at its outer end the partial gear-wheel *c''*. (See Figs. 1 and 10.) In like manner the inner bar, *d'*, of the fly *d* is pivoted in the frame-work, and has at its outer end the partial gear-wheel *d''*. Upon the main shaft *f* is rigidly keyed the arm *g*, having the inner segmental gear, *g'*, with outwardly-extending teeth, and the outer segmental gear, *g''*, with inwardly-extending teeth, the two segmental gears just described being adjacent and concentric. As the shaft *f* revolves, as indicated by the arrow in Fig. 10, and carries with it the arm *g*, the outer gear, *g''*, engages with the gear-wheel *c''* upon the fly *c*, and turns it over upon the small fly *d* and cylinders. As soon as this action is completed, the inner gear, *g'*, instantly engages the gear-wheel *c''* and turns the fly *c* back to its normal position. As the shaft *f* still further revolves, the outer segmental gear, *g''*, engages with the partial gear *d''* upon the fly *d*, turning it over upon the cylinders *e e*, and the inner segmental gear, *g'*, engaging with the gear-wheel *d''*, serves to turn the fly *d*.

back to its normal position. The operation of the several flies in the order described is continuous, and the printed sheet, which is first laid upon the upper surface of folder, (composed of fly b b' , fly c , fly d , cylinders e e' , and raised portion of frame a' a'' ,) is creased at inner line of bar b and folded over upon the flies c and d , cylinders e e' , and raised portions of frame a' a'' . Creaser b^3 in large fly b b' creases paper at inner line of bar c' . It is next folded over upon the fly d , cylinders e e' , and raised portions a' a'' by the fly c , and refolded upon the cylinders e e' and raised portion a' a'' by the fly d . Arranged centrally across the fly c is a creaser, c^3 , herein shown as pivoted in the bar c' , (see Fig. 9,) which serves to crease the sheet as it is laid upon the fly d , cylinders e e' , and raised portions a' a'' preparatory to being again folded.

In order to further fold the sheet by passing it between the cylinders e e' , I have arranged the following device upon the fly d , (see Figs. 1, 7, and 8:) h h are two inwardly-extending arms of the bar d' . At each of the ends of these arms are pivoted the double sets of metallic straps h' h' and h^2 h^2 , and to these straps is pivoted the knife h^3 . Within the knife h^3 is the curved slot h^4 , which incloses the rod h^5 , passing through the ends of the arms h h . This slot h^4 limits the throw of the creasing-knife h^3 as the fly d is reciprocated back and forth. When the fly d is in its normal position, as shown in Fig. 1, the edge h^9 of the knife is flush with the surface of the fly; but when the fly is thrown over upon the cylinders e e' the knife h^3 assumes the position shown in Fig. 8, and lies between and below the upper level of the cylinders e e' . The action of the knife h^3 , as just described, causes the partially-folded sheet to be forced between and in contact with the inwardly-revolving cylinders e e' , which carries the folded sheet below the same, dropping it upon the endless band or carrier k , and it is thereby carried to the point desired. Below the arms h h are the extensions or hangers h^6 h^6 , carrying the cross-piece h^7 . When the knife h^3 is in the position shown in Figs. 1 and 6, it lies between these hangers and upon the cross-piece h^7 . The lugs h^8 h^8 upon the knife h^3 serve to break the blow of the knife in both extreme positions. This endless band k is operated by being passed around the pulley k' , which is revolved by the belt k^2 , passing over the pulley k^3 upon the shaft f^3 . The folding-cylinders e e' are revolved in opposite directions by the driving-belt l , which passes over the pulley f^7 upon the shaft f^4 and under and over pulleys l' and l'' upon the cylinders e e' .

In Fig. 11 is shown the manner of securing the slats of the flies to the pivoted bars, such slats b^2 being rigidly fixed within the square sockets b^3 , cast integral with the bar b . The pivoted bars c' and d' of the flies c and d , when in their normal position, lie flush with the upper surface of the folder. It is necessary, for accurate folding, that these bars should be slightly raised upon their inner ends as the

flies fold the sheet, so that they will lie flush with the surface upon which they fold the sheet. I have accordingly arranged the following construction for effecting this purpose, of which m (see Figs. 4, 5, and 6) is a plate pivoted at m' in the frame-work a . At its outer end is the downwardly-projecting extension m^2 , having the curved slot m^3 . m^4 is a screw, which passes loosely through the slot m^3 and into the frame a . Underneath the plate m is the socket m^5 , between which and the frame-work a is the spiral spring m^6 . At the outer end of the pivoted plate m is pivoted the inner end of the bar c' of the fly c . c^4 is an inwardly-extending lug upon the inner end of the pivoted bar c' , and c^5 is a steel cross-plate secured to the frame a . Before the fly c is turned to fold the sheet it lies flush with the upper face of the frame, the lug c^4 lying under the plate c^5 . When the fly c is turned in the operation of folding the paper, the lug c^4 passes out from under the plate c^5 , thus permitting the spring-pressed plate m to rise, carrying with it the pivoted bar c' of the fly to such a raised position that the paper can be properly folded. When the fly c is turned back, the lug c^4 is again forced in under the plate c^5 , returning the fly to its normal flush position. The fly d is likewise arranged in a similar manner. The sprocket-wheel f^6 , for operating the folding apparatus, rests loosely upon the collar n , rigidly secured to the shaft f . The hub of the sprocket-wheel f is provided with the recess n' , within which rests the dog n^2 , between which and the collar n is the spiral spring n^3 , which operates to keep the end of the dog n^2 in the recess n' , so that in the positive rotation of the sprocket-wheel f^6 the collar n and shaft f is turned, operating the folder. When the direction of revolution is reversed, the dog n^2 slips into its recess n' in the collar n , and the shaft f does not revolve.

As a separate application is required for the peculiar construction within the hub of the sprocket-wheel just described, I hereby reserve the right to make such construction the subject-matter of another application to be subsequently filed by me.

I claim—

1. In a paper-folding machine, in combination with the large fly, the longitudinal shaft f and cross-shafts f^4 f^5 , with their bevel gear-wheels f^1 f^2 f^3 and their segmental gear f^8 f^9 and f^{10} , combined with the segmental gears f^9 and f^{11} upon the pivoted bar b of the large fly, substantially as shown and described.

2. In a paper-folding machine, in combination with either the intermediate or small fly, or both, the arm rigidly secured to the shaft f , provided with the inner and outer segmental gears g^1 and g^2 , having their teeth facing each other, in combination with a partial gear, c^2 or d^2 , upon the pivoted bars c' or d' of the flies, substantially as shown and described.

3. In a folding-machine, in combination with the pivoted bar c' of the intermediate fly, provided with the lug c^4 , the pivoted plate m , hav-

ing the outer extension, m^2 , with curved slot m^3 , the screw m^4 , upon which the slotted extension m^2 m^3 works, the spiral spring m^6 , and the plate c^5 , under which the lug c^4 passes, substantially as and for the purpose stated.

4. In combination with the fly d d' , provided with the arms h h' , the knife h^3 , provided with the curved slot h^4 in engagement with the rod h^5 , and the metallic straps h' h' and h^2 h^2 , by means of which the knife is pivoted to the fly,

such knife being adapted, as shown, to fold the sheet between the rollers e e , substantially as shown and described.

In testimony whereof I have signed my name to this specification in the presence of two subscribing witnesses.

GEORGE W. SHAMP.
